APPARATUS FOR PUMPING OIL WELLS

John A. Zublin, Los Angeles, Calif.

Application May 12, 1939, Serial No. 273,239

4 Claims. (Cl. 103—203)

This invention relates to the operation of oil wells, both flowing wells and pumping wells.

This application is a continuation in part of my application filed May 1, 1939, Serial No. 5 271,228, entitled "Method of and apparatus for producing oil and gas from a well."

In the operation of wells, in the event that there is insufficient formation pressure to lift the oil to the surface, resort to various pumping mechanisms must be had. Also, the pressure desired in the oil at the surface may be such as to necessitate pumping.

High gravity oils, and those containing a large amount of free gas, gas in solution, occluded gas, and gas associated with them in other ways, are frequently difficult to pump or compress, as the gas lessens the efficiency of the pumping mechanism by expanding and contracting as the plunger reciprocates, preventing the utilization of the full displacement of the pump for pumping purposes, and, if sufficient gas is present, preventing pumping of fluid entirely, a condition known as gas lock.

It is thus a primary object of this invention to avoid the effect of gas lock which so frequently occurs in the pumping of high gravity oil containing large amounts of free gas, dissolved gas, occluded gas, and gas otherwise associated with the oil.

Another object of this invention is to agitate the oil, causing separation of the gas and oil by mechanical means and with energy derived from the surface, and to then pump or compress the gas free oil without interference from gas.

Another object of this invention is to separate the gas and oil, and liberate the gas into the casing, before flowing the gas free oil to the pump which raises it to the surface or increases its pressure.

Another object of this invention is to simplify the actuation of the agitating means by connecting it with the pump or compressor.

Another object of this invention is to allow the oil to be separated from the gas and pumped to the surface, the gas so separated having a pressure higher than the pressure of the formation producing the oil.

Further objects will become apparent as the description proceeds.

What I propose to do is to mechanically agitate the gas oil mixture in the well by agitators driven by the pump driving means, and separate the gas from the oil by various expedients, and flow the lean oil to the pump, returning the gas to the casing.

Referring to the drawing:

Figure 1 is one form of apparatus for practicing my invention, partly in section; and

Figures 2 and 3 are other constructions, also partly in section, all figures being somewhat diagrammatic.

Referring to Figure 1, 4 represents a casing of a well with perforations 5. In the casing is an eduction tube 6. In its length, the eduction tube contains a standing valve 8. Above the standing valve 8 is a gas valve 9, the space between the standing valve and the gas valve forming an agitation and separation chamber 10.

In the casing, somewhere below the gas valve 9, is a packer 7, which may be where shown or even below the standing valve 8, on a small tubing extending therefrom. The purpose of the packer is to separate the gas from the producing zone.

In the separation chamber 10 is a series of 20 agitating elements 11, connected to a tube 12. This tube 12 passes through the gas valve 9, and is fastened to the pump plunger 13. In its length in the separation chamber 10, the tube 12 has a series of downwardly extending passageways 14, leading to its interior. At its upper end the tube 12 contains a valve 15, allowing flow in an upward direction only. The plunger 13 is of the usual construction, and contains a travelling valve 16, and is driven from the surface by a sucker rod 17, in the usual manner for pumping wells.

In operation of this device the oil gas mixture enters the eduction tube and travels up the tube 6 past the standing valve 8 into the agitation and separation chamber 10. There it is violently agitated by the reciprocation of the elements 11, causing release of a large quantity of gas. As it flows down the passageways 14, entrained gas rises, and eventually passes through the gas valves 9, to the casing, flow down the openings 14 being at a low enough velocity to allow sufficient gas to separate to accomplish the desired results. The oil rises past the valve 15, into the space below the plunger 13. From thence it is pumped to the surface by the reciprocation of the plunger. The gas, after escaping to the casing, is returned to the formation by the perforations 5, or is withdrawn at the casinghead, as desired. The packer 7 prevents the gas pressure developed by agitation from forcing the level of the oil in the production part of the casing below the bottom of the eduction tube.

In Figure 2 I have shown a different form of my invention, in which the oil is agitated in the casing rather than in the eduction tube. In this form, the casing 4 contains an eduction tube 6,

which contains a plunger 13 driven by sucker rods from the surface. Instead of tubing to drive the agitator, this form has a sucker rod 17, connecting the agitator with the pump plunger. The 5 agitator 11 operates directly in the casing, below the standing valve 18, the sucker rod 17 passing through the standing valve.

Below the standing valve 18 is a gas anchor 19, which is in effect two concentric pipes, with 10 passages therein so that oil passes down the annular space between them, before rising in the inner pipe. This construction has an operative identity with the openings 14 in the form of Figure 1.

15 In operation, in this form, the agitation of the gas oil mixture in the casing by the agitators 11 releases the gas, and the lean oil, with some entrained gas, flows down the gas anchor into the eduction tube, past the standing valves to the 20 pump, where it is pumped to the surface. The gas left in the casing may be withdrawn, used for repressuring, in the same well, through perforations in the casing, or through a different well, depending upon conditions.

25 The form of Figure 3 is similar to the form of Figure 2, in that the gas oil mixture is agitated in the casing. However, in this form the agitation is carried on by agitator elements carried by a small tube 20, connected to the plunger as in

30 Figure 1. In this form, the oil flows from below the agitator to the tube 20, and thence to the pump chamber. The intake at the bottom of the tube 20 may be a plain opening, or of the nature shown in Figure 1 at 14. In the form of Figure 3, 35 the gas is disposed of as in Figure 2; the oil path, after entering tube 20, is the same as that of Figure 1.

It is to be understood, of course, that these 40 figures are not to scale, being grossly exaggerated in width for the purpose of illustrating the principle, and in actual practice the parts in general are very much elongated.

I wish it clearly understood that the invention 45 is not to be limited by the disclosure, but by the scope of the appended claims.

It is to be understood that in all cases where the word "pumping" is used that the word is to be interpreted as meaning either pumping in the sense of lifting the oil to the surface or increasing the pressure of the oil at the pumping 50 mechanism for other purposes.

I claim:

1. Apparatus for the production of oil from a well flowing a gas and oil mixture to the casing

including an eduction tube, a pumping mechanism therein driven from the surface, a tube connected to the pumping mechanism and adapted to be actuated thereby, a chamber valved at the bottom for the entry of gas and oil, and at the top for the escape of gas, agitating elements in the chamber driven by the tube, and downwardly directed openings in the tube for admitting separated oil into the tube, whence it flows to the pumping mechanism. 10

2. Apparatus for production of oil from a well flowing a gas and oil mixture to the casing including an eduction tube, pumping mechanism in said eduction tube, a chamber having a valve at the bottom thereof for the entry of gas and oil mixture into the chamber, a tube connected to and actuated by the pumping mechanism, said tube extending into said chamber and having agitating elements thereon for agitating the gas and oil mixture to effect separation of gas and oil, openings in said tube for admitting separated oil into the tube whence it flows to the pumping mechanism, a gas valve in the upper portion of said chamber for the escape of separated gas, and packing means in the casing between said gas valve and the region of the well producing the gas and oil mixture whereby the separated gas is sealed against access to the region of the well producing the gas and oil mixture. 25

3. Apparatus for the production of oil from a well flowing a gas and oil mixture to the casing including an eduction tube, a pumping mechanism embracing a plunger driven from the surface of the ground, a tube having its upper end connected to said plunger and movable therewith, a chamber having a valve at the lower end thereof for the entry of gas and oil mixture from the well and a gas valve at the upper end for the escape of gas, said tube extending into said chamber, agitating elements in said chamber 40 driven by said tube for agitating the gas and oil mixture to effect separation of gas and oil, openings in said tube for admitting separated oil into the tube whence it flows to the pumping mechanism, and packing means in the casing between 45 said gas valve and the region of the well producing the gas and oil mixture, whereby the pressure of the separated gas does not affect the flow of gas and oil being produced.

4. A device of the type described in claim 3 50 including a valve at the upper end of said tube for controlling flow between the interior of said tube to the interior of the pumping mechanism.

JOHN A. ZUBLIN.
